UNITED STATES PATENT OFFICE.

ARLEIGH N. VAN NOSTRAND, OF FLUSHING, NEW YORK, ASSIGNOR TO TELAUTOGRAPH CORPORATION, OF NEW YORK, N. Y., A CORPORATION OF VIRGINIA.

PAPER-WINDING MECHANISM.

Application filed January 21, 1926. Serial No. 82,671.

This invention relates to improvements in paper winding mechanism and particularly to spring-actuated paper-winders such as are used in telautograph receivers.

5 The object of the invention is to provide a construction by which all danger of injury to the spring and gearing will be avoided and by which a sudden release of the spring, when removing the paper-winding drum, will be rendered impossible.

With this general object in view and some others which will be clear from the description hereinafter, the invention consists in the 15 features, details of construction and combination of parts which will first be described in connection with the accompanying drawings and then more particularly pointed out.

In the drawings:—

Figure 1 is a front elevation of a paper 20 winding mechanism embodying the invention;

Figure 2, an end elevation of the same;

Figure 3, a view of the spring barrel with its head removed;

25 Figure 4, a central sectional view, partly in elevation, of the spring barrel, spring and ratchet device, with a portion of the winding shaft in elevation; and

Figures 5, 6 and 7 are detail views illustrating the brake device.

Referring to the drawings, the paper winding reel is indicated generally at A. It comprises a roller 1 through whose axis passes a spindle 2 on which the roller 1 is 35 fitted tightly. The spindle 2 projects at each end beyond the ends of the roller, one end of the spindle being made conical, as indicated at 2^a. The other end of the spindle is toothed to form a pinion 2^b, beyond which 40 the spindle is reduced in diameter to form a collar-portion indicated at 2^c and beyond this collar-portion the spindle is further reduced in diameter to form a bearing portion 2^d.

45 To each end of the roller 1 is detachably secured a guide disk, these disks being indicated at 3. Each disk is made of sheet metal and has a central opening through which passes the spindle 2. To detachably secure each disk to the roller, it is provided with two arc-shaped key-hole slots through each of which passes a screw 4 screwed into the end of the roller, the heads of the screws being out of contact with the corresponding 55 end of the roller.

When the disk is to be put in place, the spindle 2 is passed through the central hole of the disk and the latter then slid down on the spindle and brought into a position where the large openings of the key-hole 60 slots are in line with the screws, thereby allowing the screw heads to pass through said openings. By then rotating the disk on the spindle, the screws are received in the narrow slot portions of the key-hole 65 slots, the screw heads engaging the metal of the disk at each side of said slots, thereby holding the disk to the roller. There is sufficient friction between the under sides of the screw heads and the outer face of the 70 disk to prevent the disk from jarring loose in ordinary operation. In order to remove a disk it is only necessary to give it a slight angular movement with relation to the roller to free the screws from the narrow 75 slots and bring them into the circular openings of the key hole slots, whereupon the disk may be withdrawn. In this way, the roll of paper wound upon the roller may be freed so that it may be slid off the roller. 80 For the purpose of holding the end of a paper-web the roller is provided with a paper gripping device, such as is indicated at 5. This is a plate secured to the roller, as for example, by screws indicated at 6, the 85 plate having its free margin raised slightly from the roller periphery so that the end of a web of paper may be slid beneath the said plate.

The paper winding reel is arranged to be 90 rotatably mounted in a suitable framework which also supports the spring motor device which is intended to rotate the drum. In the present example, the framework is indicated generally at B. It comprises a base 95 portion 7, arranged to be secured to the frame of the telautograph receiver, and two standards 8 and 9 each having a projecting arm, as indicated at 10 and 11 respectively.

The arm 10 has a center bearing arranged 100 to support the conical end 2^a of the spindle 2. In the present construction this bearing is adjustable and comprises a trunnion screw 12 slotted at its outer end and provided with a conical recess at its inner end. The 105 trunnion screw 12 passes through a screw-threaded hole in the arm 10 and may be locked at any position to which it is adjusted by means of a nut 13.

The arm 11 has a bearing arranged to re- 110

ceive the bearing portion 2^a of the spindle 2. This bearing is an open slot, sloping downward and inward from its open end, as shown at 14, Fig. 2. When the spindle 2 is 5 in place in its bearings, its conical end is rotatable in the conical recess in the trunnion screw 12 and the bearing portion 2^a is rotatable in the bottom of the slot 14. In this 10 position the outer face of the collar-portion 2^c runs in contact with the inner face of the arm 11, so that endwise movement of the spindle is prevented. By pulling the spindle 2 out of the slot 14, its collar-portion 2^c is 15 freed from the arm and then the coned end 2^b of the spindle may be withdrawn from the conical bearing in the trunnion screw 12, thus freeing the spindle and its attached roller from the framework.

The arm 11 is arranged to support a 20 spring motor device arranged to drive the spindle 2 and its roller. This spring motor device comprises a spring barrel 15 having a gear wheel 16 at one end and a head 17 at the other end. The barrel, including 25 its head 17 and gear wheel 16, is rotatably mounted on a drum shaft 18 which extends through a hole or bearing formed in a boss 19 carried by the standard 9 of the framework. The drum shaft has a collar 20 arranged inside the standard 9 and a washer 21 outside the boss 19. The drum shaft 18 has its inner end reduced in diameter where it passes through the head 17 of the spring barrel, whereby a shoulder is formed near 30 said end of the shaft, against which the head rests. A washer 22 is placed on this reduced end, outside the head, and the extreme end of the drum shaft is riveted to prevent 35 its removal from the barrel. Within the barrel and near the head 17 the drum shaft 18 is provided with a transverse pin 23, one 40 end of which projects a short distance radially from the spindle. On the spindle is loosely mounted a drum ratchet 24, comprising 45 a sleeve, rotatable and slidable longitudinally on the spindle, the transverse face of the sleeve nearest the pin 23 being provided with a ratchet notch arranged to coact with the pin 23. The other end of the drum 50 ratchet 24 has a counterbored portion within which there is placed a helical spring 25, which tends to force the drum-ratchet yielding 55 toward the pin 23, this helical spring reacting against the gear wheel 16. To this 60 drum ratchet 24 is riveted the inner end of a spiral spring 26 of the usual clock-spring type. The outer end of this spiral spring 26 is riveted to a resilient friction band 27, most 65 advantageously made of phosphor-bronze, which band contacts with the inner periphery of the spring barrel 15, the expansive power of this friction band being sufficient to maintain a good frictional hold of the band on the interior periphery of the spring 70 barrel, so that the power of the spring in 75

unwinding may be transmitted to the barrel, while at the same time overwinding of the spring 26 will be prevented because as the spring is wound its external diameter is reduced and the end of the friction band 27, 70 riveted to the outer end of said spring 26, is drawn inward away from the inner periphery of the spring barrel, thus gradually reducing the frictional contact between the friction band and spring barrel and eventually allowing the spring 26 to slip around 75 within the barrel to a sufficient extent to allow the spring to unwind slightly and thereby return the friction band into gripping contact with the barrel. 80

For the purpose of winding the spiral spring 26, the drum shaft 18 has its outer end provided with a hand crank 28 secured to the spindle in any suitable way, as for example, by a transverse pin 29. The inner 85 face of the crank hub has a series of ratchet notches arranged to be engaged by a spring-pressed pin 30 mounted slidably in a hole in the boss 19 and pressed outward yieldingly by a helical spring 30a.

When the hand crank is turned, the drum shaft 18 is rotated, and the ratchet tooth of the drum ratchet 24 within the spring barrel is engaged by the pin 23 so that the said drum ratchet is turned with the drum shaft 90 18. During this operation of the hand crank the gear wheel 16 and spring barrel 15 is held stationary as hereinafter described, so that the spiral spring 26 will be wound up, it being impossible to overwind the spring, 95 because as that condition is approached, the friction band 27 slips around and allows the outer end of the spring 26 to slip relative to the spring barrel. The drum ratchet 24 and pin 23 serve to prevent injury to the 100 spring if at any time the reel is allowed to race so that the momentum of the reel carries it beyond the point where the spring is entirely unwound. At this point the tendency of the reel would be to put an excessive 105 strain on the end of the spring where it is attached to the drum ratchet, were it not for the fact that the latter will be rotated in a direction to free it from the pin 23 and thus allow it to rotate freely on the shaft. 110 As soon as the spring motor is wound, the hand crank 28 and drum shaft 18 are held against backward rotation by the spring-pressed pin 30 engaging the ratchet teeth of the crank hub. The spring motor is now 115 ready to drive the paper reel to wind up the paper from the telautograph receiver.

In order to hold the spring barrel during the winding operation, the operator may hold the reel or the spring barrel with one 120 hand while turning the hand crank with the other hand. Or, if desired, the brake device hereinafter described may be applied to hold the spring barrel.

In order to retain the spindle 2 in the open 125

slot 14 of the arm 11, a suitable retaining means is provided, and this is so combined with a brake device arranged to prevent the rotation of the spring barrel that, when the 5 retaining means is operated to release the spindle 2, the brake will first be applied to the spring barrel to prevent it rotating under the action of the spring. When said retaining means is operated to bring it to a 10 position where it will retain or lock the spindle 2 in the open slot 14, the brake will be released, but not until the spindle is locked.

While the invention is not limited to the 15 specific mechanism employed for accomplishing the two functions simultaneously, in the preferred embodiment of the invention the construction is as follows:

A spring plate 31, provided with a hole 20 through which the drum shaft 18 may pass, is mounted on said shaft between the gear-wheel 16 and the collar 20. This spring plate is bowed so that its central portion is convex toward the side of the gear wheel 16. The 25 front end of the spring plate 31 carries a hook portion indicated at 32 arranged to hook over the collar-portion 2^c of the spindle and thereby prevent the removal of the spindle from the slot. For convenience in 30 operating, a thumb-piece 33 is provided, this in the present example being made integral with the hook portion. In the best embodiment of the invention, the hook portion 32 and the thumb-piece 33 are cut or stamped 35 from a piece of sheet metal, the thumb-piece being twisted into the position shown in the drawings. This piece of sheet metal is then riveted to the end of the spring plate 31. The spring-plate also has two cam devices 40 34 and 35, the latter consisting of a plate beveled off at one end, and the former being a sloped portion of the hook portion 32. These cam devices are suitably secured to the spring plate 31 on that side of the plate 45 which faces the standard 9. These cam devices are arranged with their beveled ends pointing in opposite directions, the one (34) nearest the hook-portion 32 being arranged with its beveled end pointing upward, and 50 the other one (35) having its beveled end pointing downward. Two screws, indicated at 36, are screwed through the standard 9 and its arm 11, respectively, their ends projecting into the path of movement of the 55 cam devices 34 and 35 so that, as the spring plate 31 is swung angularly about the drum shaft 18, by use of the thumb-piece 33, the cam devices 34 and 35 will ride against the ends of the respective screws 36 and thereby the spring plate 31 will be pressed against 60 the side of the gear wheel 16, thus applying so much friction to said gear wheel that the spring 26 will be unable to turn it.

The cam devices 34 and 35 not only have 65 the beveled ends, but also have flat portions,

as will be clear from the drawings, so that when the cam devices have been moved far enough for the flat portions to contact with the ends of the screws 36, there will be no tendency for the spring plate 31 to swing 70 back, but on the contrary it will be retained in its braking position.

The screws 36, of course, can be adjusted in or out to determine the braking force applied to the side of the gear wheel 16. To 75 lock the screws 36 in any position to which they may be adjusted, suitable lock nuts 37 are provided.

It will be seen that when a reel is to be removed, it is only necessary to lift up on 80 the thumb-piece 33, thereby giving an angular movement to the spring plate 31, which swings about the drum shaft 18 as an axis. During the first part of this movement the beveled portions of the cam devices 34 and 85 35 ride over the ends of the screws 36, and thereby the spring plate is tensioned and pressed against the side of gear wheel 36. This prevents the spring 26 from suddenly unwinding, as it would if there were no 90 braking means, unless the spring barrel or gear wheel were held by hand. During the latter part of the angular movement of the spring plate 31, the flat portions of the cam devices ride over the ends of the screws 36, 95 so that when the thumb-piece is released the spring plate will stay in its braking position until force is applied to return it to its original position.

As soon as the braking device has moved 100 sufficiently to apply enough friction to hold the spring barrel, the hooked portion 32 then releases the spindle 2, so that the latter may be withdrawn from the open slot and may then be pulled endwise to release its conical 105 end 2^a from the trunnion screw 12. The desired end disk 3 may then be given an angular or rotary movement relative to the roller 1, to unlock the said disk. The roll of paper which is on the roller may then be 110 slid off the latter. By replacing the disk and replacing the reel in its bearings, the locking and brake device may be swung angularly to bring the hook portion 32 down over the collar-portion 2^c of the spindle 2. 115 This locks the spindle in open slot 14 and also releases the brake.

The spring 26 may be wound up by turning the hand crank 28. This may be done, either while the brake is on, that is before 120 swinging the thumb-piece 33 down to hook the hook-portion over the spindle 2, or afterwards. In the latter case, it is necessary to keep one hand on the reel or spring barrel to prevent rotation of the reel while the 125 hand crank is being turned.

Before releasing the brake and locking the spindle 2 in place, the end of the web of paper coming from the telautograph receiver is bent over and hooked under the 130

edge of the paper-gripping device 5 and the roller 1 is given one or two turns to wind up some of the paper. When the spring has been wound and the brake released, the 5 spring motor acts on the reel to maintain a tension on the paper web. As the latter is pulled along by the paper shifter, as is customary in telautograph receiving apparatus, the reel, under the action of the spring 10 motor, winds up the paper fed to the reel by the paper-shifter. The latter may be of any desired type, a particularly suitable form being shown and described in my application, Serial No. 32,905, filed May 26, 1925.

15 What I claim is:

1. In a paper-winder, the combination, with a reel and a spindle provided with a pinion, of a spring-motor having a gear wheel arranged to engage said pinion, whereby the 20 spindle and reel are driven by the spring motor, a support in which the spindle is removably journaled, and manually operable means for locking said spindle against removal from its journals, of a braking device arranged to be brought into action to hold the spring-motor inoperative when the 25 locking means is unlocked to release the spindle, and to free the spring motor after the locking means is locked to retain the 30 spindle.

2. In a paper-winder, the combination, with a reel and a spindle provided with a pinion, of a spring-motor having a gear wheel arranged to engage said pinion, whereby the spindle and reel are driven by the 35 spring-motor, a support in which the spindle is removably journaled, manually operable means for locking said spindle against removal from its journals, and a braking device connected with said locking 40 means and arranged to hold the spring motor inoperative when the locking means is unlocked to release the spindle, and to free the spring motor when the locking means is locked to retain the spindle. 45

3. In a paper-winder, the combination, with a reel and spindle provided with a pinion, of a spring-motor having a gear wheel arranged to drive the pinion, said spring-motor comprising a spring barrel, a spiral spring within the barrel, a winding shaft for winding the spring, a ratchet device between the inner end of the spring and the winding shaft, and a resilient friction band connected to the outer end of the 50 spring and arranged to react against the inner surface of the spring barrel. 55

In testimony whereof, I have hereunto set my hand.

ARLEIGH N. VAN NOSTRAND.
